[57] CLAIM

The ornamental design for a combined pitcher and cup set, as shown and described.

DESCRIPTION

FIG. 1 is a front elevational view of a combined pitcher and cup set showing my new design;
FIG. 2 is a side elevational view thereof;
FIG. 3 is a rear elevational view thereof;
FIG. 4 is a top plan view thereof, the handle being broken away for convenience of illustration; and,
FIG. 5 is a side elevational of one of the cups thereof shown partially in section.
